UNITED STATES PATENT OFFICE.

RAMSAY CROOKS, OF NEW YORK, N. Y., ASSIGNOR TO BARABEAU, PÉRE & FILS, OF PERIGUEUX, FRANCE.

DESIGN FOR A BOTTLE OR JAR.

SPECIFICATION forming part of Design No. 16,069, dated May 5, 1885.

Application filed January 20, 1885. Term of patent 7 years.

To all whom it may concern:

Be it known that I, RAMSAY CROOKS, a citizen of the United States, residing at the city of New York, county and State of New York, have invented and produced a new and original 5 Design for Bottles or Jars, of which the following is a specification, reference being had to the accompanying drawings, forming part thereof.

10 Figure 1 is a front view of my new design for a bottle or jar. Fig. 2 is a side elevation of the same, these two views being deemed necessary to fully illustrate my design.

The discharge-piece or mouth, instead of 15 being at the top of the bottle, is projected from the upper side of the body, as indicated by A A in Figs. 1 and 2.

The standard is a circular disk attached to 20 and a part of the bottle, as shown by B B and B B. The top of the bottle has attached to it a ring or handle, C and C.

Heretofore bottles have been more or less elongated, having an aperture at the end of a neck projected straight up from the body.

The leading features of my design are and 25 for which I claim—

1. The design for a bottle or jar herein shown and described, the same consisting of base B B and reservoir E E, spheroidal in shape and having a ring or handle at the 30 top C.

2. The design for a bottle of the shape shown, having its discharge-piece projected from the upper side, as shown at A and A in the accompanying drawings, and having a 35 standard or base in a circular disk, as shown at B B.

RAMSAY CROOKS.

In presence of—

J. G. TOURNAD,
H. B. BOYD.
